CLAIM

The ornamental design for a washing brush with rod, as shown and described.

DESCRIPTION

FIG. 1 is a perspective view of a washing brush with rod, showing our new design;

FIG. 2 is a top plan view thereof;

FIG. 3 is a front end elevational view thereof;

FIG. 4 is a bottom plan view thereof;

FIG. 5 is a rear end elevational view thereof;

FIG. 6 is a side elevational view thereof;

FIG. 7 is a top plan view shown with the brush in the length-wise position.

In FIGS. 2, 4, 6 and 7 the rod has been shown broken away for ease of illustration.

FIG. 2

FIG. 3

FIG. 4
